UNITED STATES PATENT OFFICE.

HAROLD H. GODFREY, OF LOS ANGELES, CALIFORNIA.

APPARATUS FOR EXTRACTING METAL FROM ORES AND THE LIKE.

1,347,026.

Specification of Letters Patent.

Patented July 20, 1920.

Application filed August 4, 1919. Serial No. 315,272.

To all whom it may concern:

Be it known that I, HAROLD H. GODFREY, a citizen of the United States, residing at Los Angeles, in the county of Los Angeles 5 and State of California, have invented new and useful Improvements in Apparatus for Extracting Metal from Ores and the like, of which the following is a specification.

My object is to make an improved apparatus 10 for extracting metal from ores and the like, and my invention consists of the novel features herein shown, described and claimed.

Figure 1 is a perspective of an apparatus 15 for extracting metal from ores and the like in accordance with the principles of my invention.

Fig. 2 is a vertical longitudinal sectional detail on the line 2—2 of Fig. 1.

Fig. 3 is a vertical cross section on the line 3—3 of Fig. 2.

The central support 1 is rigidly mounted 20 on crosspieces 2 and 3. The support 1 is a heavy timber rectangular in cross section 25 and straight, and the crosspieces 2 and 3 serve to make a wide base so as to rigidly mount the support 1.

The bottom 4 has bearing plates 5 and 6 30 on each side of the support 1, and links 7 and 8 connect the bearing plates 5 and 6 to pivots 9 and 10 rigidly fixed to the sides of the support 1. Side bars 11 and 12 extend upwardly from the sides of the bottom 4 and a head board 13 extends across the 35 head end of the bottom 4 between the side boards 11 and 12. The bottom 4 is covered with an amalgam plate 14 and the negative pole of an electric circuit is connected to the amalgam 14 by a wire 15 so as to make 40 a cathode.

The shaft 16 is mounted in rigid bearings 45 17 and has a fly wheel 18 and a driving pulley 19 driven by a belt 20 and an eccentric or crank 21. The post 22 is pivotally mounted upon a pin 23 fixed in a bifurcated bearing 24 mounted upon a block 25, and the post 22 has a notch 26 extending from its upper end in which the eccentric 21 operates, so that as the shaft 16 rotates the 50 upper end of the post 22 is vibrated.

A link 27 is connected to the pivot pin 28 which extends through the upper end of the link 8, and a bolt 29 is inserted through the front end of the link 27 and through a 55 desired one of the holes 282 in the post 22, so that by moving the bolt 29 from one hole

282 to another the stroke of the table may be accurately adjusted to suit. The holes 282 are formed in a row concentric to the pin 28 and extending up and down in the post 60 22, so that by moving the bolt 29 downwardly the stroke of the table is shortened.

Brackets 283 are secured to the head board 13 and straddle the post 22 to hold the post upright. The operation of the belt 20 operating the eccentric 21 shakes the table end- 65 wise.

A cleat 281 is removably mounted upon the amalgam plate 14 at the tail end of the table so as to prevent the material from 70 sluicing. The head end of the table is slightly higher than the tail end, and the material is to be discharged over the cleat 281.

A trough 30 is mounted above the side 75 board 11 and has an intake spout 31 in which the pulp is to be discharged and has a series of perforations 32 in its bottom for distributing the pulp along the table just inside of the side board 11. The table 80 slopes downwardly from the side board 11 toward the side board 12, so that the pulp will run crosswise of the table and crosswise of the line of reciprocation. The trough 30 extends half way from the head 85 of the table toward the other end.

Bars 33, 34 and 35 extend across the table and the trough 30 is mounted upon the bars 33, 34 and 35. Adjusting screws 36 and 37 extend upwardly from the side 90 boards 11 and 12 through the ends of the bars 33, 34 and 35, there being adjusting nuts 38 upon the screws below the bars and adjusting nuts 39 upon the screws above the bars, so that by manipulating the nuts 38 95 and 39 the bars may be raised or lowered.

A perforated sheet metal plate 40 is attached to the bars 33, 34 and 35, said plate fitting against the lower faces of the bars, so that the plate 40 is below the level of the 100 upper edges of the sides 11 and 12, and so that when the pulp is flowing upon the table the plate 40 will be in contact with the upper face of the pulp.

The positive pole of the electric circuit is 105 connected to the plate 40 by the wire 41 so as to make an anode.

In the practical operation the electric circuit is turned on and the belt 20 operated from any suitable source of power to operate 110 the shaft 16 and reciprocate the table, and as the table fills with pulp the electric cur-

- rent will flow from the anode 41 through the pulp to the cathode 15 and the gold will be precipitated upon the amalgam plate 14 and the water and mud will overflow the cleat 29.
- 5 The shaking of the table will effectually prevent the deposit of mud upon the amalgam plate. When the amalgam plate is loaded with gold to the desired extent the plate 40 may be raised and the gold removed from the amalgam plate.

10 Thus I have produced an apparatus for extracting metal from ore and the like comprising an ore concentrating shaking table covered with an amalgam plate electrically connected to form a cathode, and a second plate adjustably and removably mounted above and parallel with the amalgam plate and electrically connected to form an anode.

15 It is obvious that the anodes and cathodes may be reversed. The anode is made out of iron when gold and silver is extracted, but when other metals besides gold and silver are treated suitable metals are used for the anode and cathode. It will be understood that the metal contained in the pulp must be treated by a suitable electrolyte to dissolve the same, for instance, for gold, potassium cyanide is used, and for copper, sulfuric acid, or the like, as will be understood by those skilled in the art.

20 It is hardly necessary to mention the fact that the electric current passes from the anode to the cathode through the pulp, and through the pulp only. The supporting bars spacing the anode from the cathode are made either of non-conducting material or are insulated so as to prevent a current passing therethrough.

25 Various changes may be made without departing from the spirit of my invention as claimed.

I claim:

1. An apparatus for extracting metal from ore including an ore concentrating shaking table inclined longitudinally and transversely, said table being covered with a cathode, and an anode spaced above said cathode.

2. An apparatus for extracting metal from ore including an ore concentrating shaking table, a cathode covering said table, and a plate spaced above and parallel to said table forming an anode.

3. An apparatus for extracting metal from ore including an ore concentrating shaking table inclined longitudinally and transversely, a cathode covering said table, and a plate spaced above and parallel to said table forming an anode.

4. An apparatus for extracting metal

from ore including an ore concentrating shaking table, a cathode covering said table, a plate spaced above and parallel to said table forming an anode, and means for adjusting said plate up or down with relation to said table.

5. An apparatus for extracting metal from ore including an ore concentrating shaking table, a cathode covering said table, and a perforated plate spaced above said table forming a cathode.

6. An apparatus for extracting metal from ore including an ore concentrating shaking table, a cathode covering said table, a plate spaced above said table forming an anode, and a trough mounted on said table to discharge into said table at one side of said plate.

7. An apparatus for extracting metal from ore including an ore concentrating shaking table, inclined longitudinally and transversely, a cathode covering said table, a plate spaced above said table forming an anode, and a trough mounted on said table at the higher side thereof to discharge into said table between its higher side and the adjacent edge of said plate.

8. An apparatus for extracting metal from ore including an ore concentrating shaking table, a cathode covering said table, bars extending across said table, a plate secured to said bars above the bottom of said table and forming an anode, screws upstanding from the sides of said table through the ends of said bars, and nuts on said screws above and below said bars.

9. An apparatus for extracting metal from ore including an ore concentrating shaking table, a cathode covering said table, bars mounted on said table and extending thereacross, a plate secured to said bars above said table and forming an anode, and a trough mounted on said bars at one side of the table for discharging into the table between said side and the adjacent side edge of said plate.

10. In an apparatus for extracting metal from ore, an ore concentrating shaking table, a cathode covering the bottom of said table, an anode above said cathode, a post pivotally mounted at its lower end and provided with a plurality of holes, a link connected at one end to said table and a pin for pinning the other end of said link through any of said holes to said post for adjusting the stroke of the table.

In testimony whereof I have signed my name to this specification.

HAROLD H. GODFREY.
